United States Patent Office

Des. 209,037
Patented Oct. 31, 1967

209,037

BOW TIE

John F. Kossow, 3513 50th St. S.,
Tampa, Fla. 33619

Filed Dec. 1, 1966, Ser. No. 4,876

Term of patent 14 years

(Cl. D2—353)

FIG. 1

FIG. 2

FIG. 1 is a front elevational view of a bow tie showing my new design, the broken line partial showing of a collar being for purposes of illustration only; and

FIG. 2 is a top plan view of the bow tie shown in FIG. 1.
I claim:

The ornamental design for a bow tie, as shown and described.
